UNITED STATES PATENT OFFICE

169,121

BREADBOX

Clarence M. Burroughs, Glendale, Calif.

Application April 25, 1952, Serial No. 19,482

Term of patent 7 years

(Cl. D44—5)

To all whom it may concern:

Be it known that I, Clarence M. Burroughs, a citizen of the United States, residing at Glendale, in the county of Los Angeles and State of California, have invented a new, original, and ornamental Design for a Bread Box, of which the following is a specification, reference being made to the accompanying drawing, forming a part thereof.

Fig. 1 is a perspective view of a bread box showing my new design;

Fig. 2 is an end elevational view; and

Fig. 3 is a rear elevational view.

I claim:

The ornamental design for a bread box, as shown.

CLARENCE M. BURROUGHS.
